UNITED STATES PATENT OFFICE.

HENRY M. SAMPSON, OF TONKAWA, OKLAHOMA.

DESIGN FOR A DOLL.

Application filed January 21, 1922. Serial No. 312. Term of patent 14 years.

To all whom it may concern:

Be it known that I, HENRY M. SAMPSON, a citizen of the United States, residing at Tonkawa, county of Kay, State of Oklahoma, have invented a new, original, and ornamental Design for a Doll, of which the following is a specification, reference being had to the accompanying drawing, forming a part thereof.

In the drawing:—

Figure 1 is a front elevation of the doll.
Figure 2 is a side elevation of the doll.

I claim:

The ornamental design for a doll, as shown.

HENRY M. SAMPSON.
